UNITED STATES PATENT OFFICE.

WILLIAM H. ECKERT AND JOHN A. SEELY, OF NEW YORK, N. Y.

TELEPHONE SYSTEM.

SPECIFICATION forming part of Letters Patent No. 288,627, dated November 20, 1883.

Application filed May 28, 1883. (No model.)

To all whom it may concern:

Be it known that we, WILLIAM H. ECKERT and JOHN A. SEELY, citizens of the United States, residing in the city, county, and State 5 of New York, jointly, have invented a new and useful System for Telephonic Intercommunication, of which the following is a specification.

Our invention has for its object the adapting of a series of private lines centering at an office common to all of them for telephonic use.

In hotels the annunciator system commonly in use consists of a series of electrical conductors—one for each guest-room—centering at an annunciator-board in the clerk's office; and it is to such a system of conductors that we adapt telephones, so that any guest may call the clerk and communicate with him through 20 the telephone, and so that the clerk may call a guest and communicate with him in like manner, and also so that two individual wires may be joined at the clerk's office, thereby enabling two guests to converse telephonically.

While we suggest the adaptability of our invention to annunciator systems of hotels, we also design it for use in ordinary city telephone-exchanges as well.

In carrying out our invention we wholly dispense with the use of local batteries in the guests' rooms, both for the purpose of charging the primary coil of the telephone-transmitters and for calling the clerk or attendant at the central office; and, furthermore, we 35 employ only a single battery, which is placed at the central office, for every purpose whatsoever in the system. By means of this single battery the primary circuits of all the telephone-transmitters are supplied. Each guest's line is 40 connected by the guest with said battery to call the central office, and the central-office attendant can connect any individual line with the battery to call the guest to whose room it communicates.

To the end of accomplishing these results we employ, in addition to the series of individual lines or conductors—one to each room—a common conductor containing a battery which is normally and constantly closed, 50 and which runs to all of the rooms of the hotel. The primary circuit of each guest's transmit-

ting-telephone is included in said common circuit. The common circuit, or "battery-circuit," as we will term it, is provided at each guest's room with a normally-open branch, and said branch, by means of a key or switch, may be joined to the corresponding individual line, while at the same time said individual line will be disconnected from its normal earth-connection. When the battery-circuit is thus 60 joined to an individual line by a guest or subscriber, a circuit is completed from the central office or station to the guest's room, and thence back to the central office and through an annunciator-drop. The attendant at the central office may in like manner disconnect any individual line from its earth-terminal and connect said line to the common battery-circuit, and thereby complete a circuit through the battery, the battery-circuit, and to and 70 over any individual line, and thence to earth at the guest's room through a call apparatus.

We will now explain our invention by reference to the accompanying drawings.

Figure 1 is a general diagram of our entire 75 system; and Fig. 2 is a device consisting of two switch-plugs and a cord for joining any two lines with each other, and at the same time disconnecting said lines from their earth-connections at the central station.

T is an ordinary contact-transmitter, having an induction-coil, located at a central station, and T' and T² are similar transmitters placed in the rooms of different guests.

A is the battery-circuit, beginning at earth 85 G and terminating at G', which embraces battery B and the primary coils of all of the telephonic transmitters in the system. Line A also includes a resistance, R, for a purpose to be hereinafter described.

Each room or subscriber is provided with an individual telephone-line, and in Fig. 1 two such lines are shown. The line C, beginning at E, embraces the coils of annunciator-drop M, wire C', spring-jack N S, wire C², telephone-switch arm L, anvil h, wire C³, push-button or key K, anvil d, call-bell C B, and wire C⁴, thence passing to earth E'. In like manner the circuit of line D is completed from E², through M', N' S', D², L', D³, K', b, D⁴, C B', D⁵, 95 to earth E⁵.

As the telephonic apparatus for each room

or subscriber is the same as that of all the others, a description of one will serve for all.

Each room or subscriber is provided with an automatic switch, which operates, when the telephone is out of use, to divert the individual-line circuit from the telephonic transmitters and receiver, and to direct it through a call-bell, C B'. Thus, when telephone-receiver H' is hung upon lever L, said lever is depressed 10 against the action of spring s into contact with anvil h; but when the telephone is removed from the lever it is raised against contact-point g, and the circuit of line D is completed, not through call-bell C B to earth E', but instead 15 through wire 5, telephone-receiver H', wire 6, to binding-post 3, the secondary coil of transmitter T', to binding-post 4 and wire 7, to earth at E'. Each line and telephone set is also provided with a key or push-button, K, and, as 20 shown in the drawings, when not depressed, the individual line is completed through C B to earth; but when depressed the individual line is disconnected from the call-bell and is joined through stop e, wire 11, to point i of 25 battery-line A, and thereby, upon depressing key K, a battery-circuit is thrown on C from A, and station X is enabled to call up the central office.

At the central station, or clerk's office, each 30 line is provided with an annunciator-drop, as M; to indicate a call from station X. Normally, line C is connected to earth through spring-jack N S; but after receiving a call from station X it is necessary that the central-office attendant connect himself with station X by telephone to ascertain what is wanted. For this purpose he depresses a lever-arm, L', and raises spring S against stop p, when line 35 C from station X is broken from M, and is completed through p f n F', receiving-telephone H, wire F, binding-post 3 of transmitter T, the secondary coil of said transmitter, binding-post 4 and F, to earth G'. The central-office attendant having depressed lever 40 L', and thereby placed his telephone in circuit, and the operator at station X having removed his telephone H' from L, it is apparent that words spoken into transmitter T' will cause current-impulses in the primary coil of T, which in turn will set up impulses in the 45 secondary coil of said transmitter, thereby causing a reproduction of speech in telephone-receiver H. In the same manner, words uttered into transmitter T by the central operator will be reproduced in receiver H'. If 50 the central operator is apprised that the operator at X desires to converse with Y, he turns a spring-jack plug or wedge, I', upon its center y', thus thrusting said plug between spring S' and block N'. The upper portion 2 of the wedge is of conducting material, while the lower is an insulating-piece. When the wedge is pressed between S' and N', it being connected by wires q' and N' to battery-line A 55 at j, the individual line is first disrupted at the spring-jack, and is then connected to the

battery-line. By this means line D² is charged with a current and bell C B' is rung. The central operator may then inform Y what is wanted by telephone upon depressing lever 7c L². The two subscribers at X and Y being in readiness to converse, wedge I is removed from the spring-jack, when switch-plugs V' I' and V I², joined by conductor x, are placed in spring-jacks N' S' and N S, and N S, N S', 75 V, and V' being of metal, S' and S are connected. In this way the two lines are disrupted at the central station from their normal earth-connections and from their annunciator-drops M' and M, and are connected together through conducting-cord x. 80

When key K is depressed at station X, line C is connected to battery-line A; and in order that a considerable current may be obtained upon line C from battery B, it is necessary 85 that a resistance, R, be inserted in line A near its terminal G'; otherwise the potential of points along A, near G', would be too low to cause C to receive sufficient current to operate annunciator M, and current from battery 90 B, instead of flowing over C, would pass directly to earth G'.

From the foregoing it is seen that the battery-circuit is permanently connected to all of the transmitters in the system, said line on 95 the battery side of the transmitters being connected to the primaries of the induction-coils thereof at posts 1, while the other sides are connected to line A at post 2. The battery-line, in addition to embracing the primary of 100 the induction-coil for each local station, is also provided at points i and i' and j, respectively, with normally-open branches 11, 12, and N'; and in connection with branches 11 and 12 there are keys K and K', respectively, which 105 normally complete individual lines through said bells at the local stations, while upon depressing K or K' the individual line in which it is placed is broken and diverted from the call-bell to the common battery-circuit. 110 Branch N' is also provided with means, as shown, for breaking the individual lines from their normal earth-connections and connecting said individual lines by branch N' to the common battery-circuit. 115

In order that K may be manipulated to send impulses over the individual line to actuate drop M, it is obvious that the receiving-telephone must remain upon its supporting-bar, for, if removed, lever I' will leave contact h, thereby permanently disrupting the individual line at h, and rendering it incapable of being connected to the battery-circuit by key K. 120

In order that the telephone-instruments of the central operator may be placed in connection with any particular individual line, the conductor F F' F², containing the telephone transmitter and receiver, is provided with as many divergent branches f f' as there are individual lines; and each of said branches, as 125 f', may be connected to its respective line through point p' and spring S'. In like man-

ner, in order that all of the individual lines may be connected to the battery-circuit through branch N^o, said branch is divided into as many sub-branches q q' as there are individual lines; 5 and any sub-branch, as q', may be intermittently joined by plug I' with individual line D to ring the alarm C B'.

What we claim, and desire to secure by Letters Patent, is—

- 10 1. A series of individual telephone-lines which are unprovided with battery centering at a central station, in combination with a single line permanently closed and provided with battery, running from said central station to telephone-stations upon the individual lines, and means for connecting the individual lines to the battery-line, as described.
- 15 2. A line joining a central station with a series of telephone-stations, which is permanently closed and provided with battery, and a series of telephonic transmitters, in combination with a series of individual telephone-lines separately connecting the local stations with the central station, and means for joining the individual lines to the battery-line, substantially as specified.
- 20 3. A telephonic line permanently closed and provided with battery common to a central station and a series of local stations, having at each of said stations a telephonic transmitter and the primary coil of an inductorium forming a section or part of said line, in combination with a series of independent individual lines centering at the central station and separately passing through the several stations, and means for connecting a telephonic receiver and the secondary coil of a transmitter-inductorium to an individual line either at a local station or at the central station.
- 25 4. As a means for enabling a telephonic system to be operated without the use of battery at local stations, the combination of one line having an earth return closed and permanently provided with battery at the central station, said line including the telephonic transmitters of the system and corresponding primary inductorium-coils, and corresponding secondary inductorium-coils and telephone-receivers adapted to be included in the respective individual lines of the system, and means for connecting individual lines to the battery-line.
- 30 5. The combination of a series of individual telephone-lines, each of which is provided at a local station with a call-bell or signaling device normally in circuit, and a key or push-button for connecting said individual line

with a common battery-line, (said common battery-line being permanently closed and provided with battery,) and for removing the 60 call-bell from circuit, and a common battery-line whereby a local station may be called up, and may also call the central stations, as described.

6. In combination with a common battery-circuit which is permanently closed and provided with battery, one or more individual telephone-lines normally connected to earth at each local station through a call-bell, means for cutting out the call-bell and connecting 70 said individual line to the battery-circuit, and a telephone-switch for also cutting the individual line and connecting it through a branch including the secondary coil of the transmitter.

7. The combination, at the central station, of 75 means for receiving a signal from any local station, means for disconnecting the individual line from its normal earth and for connecting said line to the common battery-line for calling the local station, and means for disconnecting the normal earth of the individual line and for connecting said individual line through a branch at the central station including a telephone-receiver and the secondary coil of a transmitter whose primary coil is 80 in the battery-circuit.

8. A series of individual telephone-lines which center at a central office, two normally-open branches for each individual line at said central office, means for connecting said 90 branches to said individual line, one to connect said individual line to a common battery-circuit and the other to connect the individual line to earth through a telephonic receiver and transmitter, all in combination as described. 95

9. In a telephone system, the combination, at a central station, of a series of main lines, a common battery-line, a normally-open branch for joining any individual line to the battery-circuit, a second normally-open branch independent of the battery-line, containing a telephonic transmitter and receiver to which any individual line may be joined after it is broken from its normal earth, and means for disconnecting the individual lines from their earth- 100 connections at the central office and joining them together in pairs. 105
